HEATER

William J. Payne, Georgetown, Ky.

Application August 18, 1941, Serial No. 407,346

4 Claims. (Cl. 237—7)

This invention relates to heaters and more particularly to automatic controls for heaters of the type in which the heat exchange device is closely associated with the source of heat.

An object of the invention is to provide a device of the character indicated with means associated with the heat exchange device for controlling the supply of fuel to the heat producing device.

A further object of the invention is to provide a device of the type indicated, in which the heat exchange device includes a condenser unit in conjunction with a liquid, vapor or steam with means responsive to temperature variations in said liquid, vapor or steam for controlling the supply of fuel and thereby the heat input; and further, to associate means for providing an improved venting and the elimination of entrained air or the formation of water pockets or other objectionable features.

The invention consists in the novel construction, arrangement and combinations of parts hereinafter more particularly described and claimed.

One sheet of drawings accompanies this specification as part thereof, in which like reference characters indicate like parts throughout.

In the drawing:

Figure 1 is a diagrammatic side elevation of the operative parts of the present invention.

Figure 2 is a front elevation largely diagrammatic of Figure 1.

Figure 3 is a cross section taken on line 3—3 of Figure 2.

Figure 4 is a cross section taken on line 4—4 of Figure 2.

The invention is herein illustrated and described in connection with a socalled unit heater in which gas is utilized as a fuel, associated with a condenser through which air is driven or sucked by a fan to heat a room or building.

Referring to the drawing, the condenser or heat exchange device comprises a top header 1, a bottom header 2 which communicate through a plurality of spaced condenser tubes 3. A fan 4, driven in any desirable manner operates to either draw or force air between the condenser tubes.

The bottom header 2 communicates, as by pipe 5, with a liquid container 6 which is preferably provided with a gauge 7 through which liquid level can be observed.

Gas burners 8 are positioned below the liquid container 6 and are herein illustrated as two circular burners of standard construction, each having two ring burners, each outer ring 9 being provided with its separate feeder pipes 11 and 13

while the two inner ring burners 10—10 are connected by pipes 14—14 to a common feeder pipe 12. The feeder pipes 11, 12 and 13 extend to a gas header 15 which is connected by a pipe 16 to the gas supply source. In each of the feeder pipes 11, 12 and 13 is positioned a control valve 17, 18 and 19 respectively of the steam gas thermocontrol type and the steam sections of these thermocontrol valves 23—24—25 are associated with stand pipes 20, 21 and 22 which communicate with the liquid container 6. One of these stand pipes 20 extends above its thermocontrol valve 17 and is provided with a pressure gauge G. Another stand pipe 22 extends above its thermocontrol valve 19 and is associated with a fourth gas steam thermocontrol valve 26—27, the gas control portion of which 27 is associated with a pilot supply pipe 28 which communicates with a pilot burner 29 adjacent the burners, being controlled by a manual valve 30, and at its other end with a pilostat valve 39 interposed in the gas supply pipe 16. One of the stand pipes 22 is connected with a by-pass pipe 31 to the top header 1 of the condenser unit and has on its upper end an air vacuum valve 32 for venting entrained air.

The pilostat valve 39 may be of any well known type in which the valve controlling the passage of gas through the main pipe 16 is closed when the passage of gas through the small pilot feed pipe 28 is stopped. The steam gas valves 17—23, 18—24, 19—25 and 26—27 are all of the well known type in which variations in temperature beyond predetermined points will operate to close the gas valve.

The steam gas valve 26—27 which controls the flow of gas through the pilot feed pipe 28 is preferably set for the highest working temperature range, for instance, 230°—240° while the steam gas valve 17—23, 18—24 and 19—25 which control the respective burner feed pipes are set for varying temperature ranges below that of the pilot control valve, such as ranges of 215°—220° for one; 220°—225° for another, and 225°—230° for the third.

A desirable liquid for use in the liquid reservoir has been found to be distilled water and an antifreeze such as "Prestone."

In operation, and starting with the device cold, all of the steam gas thermocontrol valves will be open. Upon lighting the pilot burner 29 through operation of the manual valve 30, the pilostat valve 39 will be open thus permitting a flow of gas through pipe 16, header 15 and

feeder pipes 11, 12 and 13 to all of the burner units.

After the liquid in container 6 has vaporized and the ratio of heat input and heat output of condenser changes by reason of the raising of the room temperature so that the heat input exceeds the heat output, the rise in temperature of the steam, vapor or hot water in the stand pipes 20, 21 and 22 will cause the operation of the steam gas thermocontrol valves 17, 18 and 19 in the consecutive order indicated closing the respective gas feed pipes 11, 12 and 13 in the same order so that as the heat input rises, the number of burners in operation will successively be reduced so as to maintain a relatively constant ratio between the heat input supplied to the condenser, heat exchange unit, and the amount of heat output taken therefrom by the air being forced through the same.

Where, by reason of special emergency circumstances, this heat ratio rises excessively to the range controlled by the steam gas thermocontrol valves 26—27, these valves will operate thus closing off the flow of gas through the pilot feeder pipe 28 and thereby operating the pilot stat valve 39 to shut off completely the supply of gas from the entire device.

By reason of the by-pass 31 communicating with the top header 1 with one of the stand pipes 22, it has been found that the flow of condensate through the condensing tubes 3 is greatly facilitated and made more uniform and the formation of air pockets and the like substantially eliminated.

It will be understood, of course, that the burners, stand pipes and valves will be preferably enclosed in a suitable casing, which, however, is not essential to the operation of the device and, therefore, not illustrated herein.

It will further be understood that any number of burner units with their corresponding feed pipes and control valves can be utilized and that various modifications of structure will permit the utilization of the invention in a great variety of forms.

Having thus described my invention, I claim:

1. In a gas heater the combination of a plurality of gas burners, a gas supply pipe, a gas header and a plurality of gas feed pipes, one connecting each gas burner to the gas header, with a thermocontrol valve in each of the gas feed pipes, said thermocontrol valves set to operate over different heat ranges and positioned to be responsive to the heat output of the burners, a pilostat valve in the gas supply pipe, a pilot burner, a pilot supply pipe connecting the pilostat valve and the pilot burner, and a thermocontrol valve responsive to the heat output of the burner in the pilot supply pipe set to operate over a temperature range higher than the thermocontrol valves in the burner feed pipes.

2. A gas heated steam or vapor heating con-

denser unit comprising headers connected by condensing tubes with means for forcing air between said tubes, a liquid container positioned beneath the bottom header and communicating therewith, a plurality of gas burners positioned below and in heat exchange relation to the liquid container, a gas supply pipe, a gas header, a plurality of feed pipes each connecting the gas header with a burner, a thermocontrol valve for each of said feed pipes, a plurality of stand pipes each communicating with the liquid container and with a thermocontrol valve controlling one of the gas feed pipes, a pilot burner, a pilostat valve in the gas supply pipe, a pilot feed pipe connecting the pilostat valve and pilot burner, and a thermocontrol valve in one of said stand pipes and pilot feed pipe controlling said pilot feed pipe.

3. A gas heated steam or vapor heating condenser unit comprising headers connected by condensing tubes with means for forcing air between said tubes, a liquid container positioned beneath the bottom header and communicating therewith, a plurality of gas burners positioned below and in heat exchange relation to the liquid container, a gas supply pipe, a gas header, a plurality of feed pipes each connecting the gas header with a burner, a thermocontrol valve for each of said feed pipes, a plurality of stand pipes each communicating with the liquid container and with a thermocontrol valve controlling one of the gas feed pipes, a pipe connecting one of said stand pipes with the top header and an air-vacuum valve connecting said last mentioned stand pipe to the atmosphere.

4. A gas heated steam or vapor heating condenser unit comprising headers connected by condensing tubes with means for forcing air between said tubes, a liquid container positioned beneath the bottom header and communicating therewith, a plurality of gas burners positioned below and in heat exchange relation to the liquid container, a gas supply pipe, a gas header, a plurality of feed pipes each connecting the gas header with a burner, a thermocontrol valve for each of said feed pipes, a plurality of stand pipes each communicating with the liquid container and with a thermocontrol valve controlling one of the gas feed pipes, said thermocontrol valves controlling the gas feed pipes being set to cover different temperature ranges, a pilot burner, a pilostat valve in the gas supply line, a pilot feed pipe connecting the pilostat valve and pilot burner, a thermocontrol valve in one of the stand pipes and pilot feed pipe controlling the pilot feed pipe, a pipe connecting said stand pipe with the top header of the condenser and an air-vacuum valve on said stand pipe communicating to atmosphere.

WILLIAM J. PAYNE.
